SHOTSHELL WAD STRUCTURE

Arthur S. Yeomans, Jr., North Haven, Conn., assignor to Olin Mathieson Chemical Corporation, a corporation of Virginia

Filed May 12, 1959, Ser. No. 812,768
1 Claim. (Cl. 102—42)

The present invention relates to cartridges and in particular to wad assemblies utilized in cartridges.

In the subsequent description of the several disclosed embodiments of the invention, as well as in the claim, the language "cartridge" is intended to include so-called shotshells.

In addition, it is intended that the invention will find equal application in cartridges powered by any fast burning propellant be it liquid or powder.

Furthermore, the invention is readily adaptable to cartridges carrying a single projectile or bullet as well as to cartridges carrying a plurality of projectiles commonly termed "shot."

A feature of the invention is the provision of a novel cartridge.

A further feature of the invention is the provision of a novel cartridge wad assembly.

A still further feature of the invention is the provision of an exceedingly tight gas seal means between the propellant cavity and the projectile cavity of a cartridge.

A further feature of the invention is the provision of a cartridge wad assembly including several wad elements and a cartridge case wherein one wad element is effective to contact and to drive another wad element into tight contact with the interior of the cartridge case thereby effecting a positive gas seal.

A cartridge wad assembly embracing certain principles of the invention may comprise a tubular cartridge case or body having a propellant cavity and a projectile cavity separated by a two element wad, one wad element being formed with a concave contour and the other wad element being formed with a convex contour, said elements being operative to engage one another in the region of said contours so that one element is effective to swell the other radially to develop a peripheral seal in the interior of the cartridge case.

Other features and advantages will become more apparent from the succeeding specification when read in conjunction with the appended drawings, in which:

FIG. 1 is an elevational view, partially in section, showing one embodiment of the invention.

FIG. 2 is a similar view of another arrangement of the invention, and

FIG. 3 is still another embodiment of the invention.

Referring now to the drawings, the reference numeral 10 represents a cartridge having a body or case 11 embracing a projectile cavity 12 and a propellant cavity 13.

Disposed between and physically separating the projectile cavity and the propellant cavity is a pair of wads comprising a wad element 14 having a generally concave contour as at 16 and a wad element 17 having a generally convex contour as at 18.

The respective concave and convex contours are disposed in nested relationship and normally make a line contact as at 19.

2

While the particular convex and concave contours of the disclosed embodiments of the wad elements define cones making circular line contact, it is not intended that the contours be so limited. As will be more apparent hereinafter, any generally concave and convex surfaces will suffice so long as there is a wedging action between the wads in which the lower wad (wad 17) tends to flare, swell or "mushroom" the upper wad element radially into tight peripheral contact with the interior of the cartridge case.

In the FIG. 1 embodiment of the invention a so-called cup wad 21 (cup-shaped) is disposed between the wad element 17 and the propellant cavity as an individual element.

In the embodiment of FIG. 2, the cup wad is formed integral with the wad element nearer to the propellant cavity wherein the wad 17 is formed with a skirt 23.

The FIG. 3 embodiment illustrates another individual wad element defining an "H" wad 24 disposed between the wad element 17 and the propellant cavity 13. The wad 24 obviously includes a cup-like structure.

Upon activation of propellant within the cavity 13 utilizing a primer 26 in well-known fashion, the propellant burns rapidly to generate hot gases developing pressures of the order of 8,000 to 10,000 p.s.i.

The gas pressure first operates upon the cup-like structure of the wad assembly driving the skirts or flanges 23, 27 and 28 into tight gas sealing contact with the periphery of the interior of the cartridge case.

Instantaneously the gas pressure begins to drive the cup-like portion of the wad assembly away from the propellant cavity with the result that the next adjacent wad element 17 is driven into wedging relationship with the upper wad 14.

The wedging action, which occurs because the slope of the contour of the lower wad is flatter than the slope of the upper wad, is effective to flare, swell or mushroom the upper wad in a radial direction effective to create an even tighter gas seal between the interior of the cartridge case.

The occurrence of the wedging action also affords cushioned but positive thrust in driving the projectile from the projectile cavity. The cushioned effect is a function of the space between the contoured wads and is increased, of course, by certain cup wad structures such as the H wad of FIG. 3.

In operation, the cup-like structure of the wad assembly may be thought of as creating a primary seal while the combined concave and convex contoured elements thereof create a secondary seal and virtually insure a gas tight barrier or gas tight piston between the propellant cavity and the projectile cavity.

What is claimed is:

In a shotshell having a propellant cavity and a shot column separated by a cup wad defining a primary seal, the improvement which comprises a pair of cooperating wads disposed between the shot column and the primary seal effective to create a secondary seal, said cooperating wads defining a top wad having a substantially concave face, a bottom wad having a substantially convex face, the radius of curvature of a circle described so that it is

tangent to said concave face at at least two points being less than the radius of curvature of a circle described so that it is tangent at at least two corresponding points of said convex face, said cooperating wads being partially telescoped so that the respective concave and convex faces make line contact with one another, said line contact defining a circle whose diameter is substantially equivalent to the internal diameter of the shotshell so that upon firing the shotshell the cooperating wads undergo maximum compression along said line of contact.
